UNITED STATES PATENT OFFICE.

NATHAN WEISS, OF NEW YORK, N. Y.

DESIGN FOR A BOX FOR CIGARS OR CIGARETTES.

SPECIFICATION forming part of Design No. 29,056, dated July 19, 1898.

Application filed June 16, 1898. Serial No. 683,619. Term of patent 7 years.

To all whom it may concern:

Be it known that I, NATHAN WEISS, a citizen of the United States, and a resident of the borough of Manhattan, city and State of New York, have invented a certain new and useful Design for Cigar or Cigarette Boxes, of which the following is a specification, reference being had therein to the accompanying drawings, in which—

- 10 Figure 1 is a longitudinal sectional view, Fig. 2 a transverse section, and Fig. 3 a bottom perspective, of my new design for a box. The body of the box consists of the bottom *a*, two longitudinal sides *b*, the end portions *c*, and the top *d*. The bottom of the box is fluted—that is, it is provided with a series of longitudinal depressions *e*, running substantially the full length of the box and side by side entirely across the box, said depressions 15 being curved in cross-section and lying close together, so as to form longitudinal ridges *f*. These depressions at their ends are rounded into the end pieces *e*, as at *g*. The end pieces *e* are flat and stand at right angles to the bottom, whereas the side pieces *b* are provided with a channel *h* along their upper edges. The channels run the full length of the box

and are closed at their rear ends by the rear end portion *c*, the forward ends of the channels being open, the forward end portion *c* being 30 notched at *i* for this purpose. It will be observed that the depressions that are adjacent the sides *b* round nicely into the same, thereby making the lower longitudinal corners of the box rounding, as at *j*. 35

The top *d* entirely closes the box and has its longitudinal edges lying into the channels *h*, forming bead-like portions *k*. The forward end of the top is provided with a lip *l*, and near its rear edge the top is provided with 40 two depressions *m*, one near each corner. The top lies flush with the upper edge of the rear end portion *c*.

I claim—

The design for a cigar or cigarette box substantially as herein shown and described. 45

In testimony whereof I hereunto affix my signature, in the presence of two witnesses, this 14th day of June, 1898.

NATHAN WEISS.
